UNITED STATES PATENT OFFICE

HARRY M. PFLAGER, OF ST. LOUIS, MISSOURI, ASSIGNOR TO GENERAL STEEL CASTINGS CORPORATION, OF GRANITE CITY, ILLINOIS, A CORPORATION OF DELAWARE

RAILWAY CAR STRUCTURE

Application filed June 1, 1931. Serial No. 541,456.

This invention relates to railway rolling stock and consists particularly in a novel construction of side or end sills for car underframes and the assembly therewith of the car walls and floor.

In ordinary construction the car floor rests on top of the underframe sills and abuts on the inner face of the car wall, forming a joint which usually results in a crevice within which coal dust, cinders, other dirt, and water may accumulate. Sulphuric acid and other corrosive agents from these deposits attack the adjacent portion of the wall, especially where the wall is composed of metal plates, necessitating repair and renewal of the wall.

The main object of the present invention is to provide an underframe having a novel sill structure including an element extending above the level of the top surface of the floor and arranged for attaching the wall so that the joint between the latter and its mounting member is spaced above the floor, thereby avoiding the objectionable crevice and resulting corrosive action referred to above.

Further objects of the invention are to provide a strong, rigid, economical underframe structure adapted to readily mount the car walls and associated framing with a minimum amount of machining.

I attain these objects and others in the structure illustrated in the accompanying drawings in which—

Figure 1 is a partial top view of an underframe embodying my invention.

Figure 2 is a side view of the same.

Figure 3 is a vertical transverse section taken on lines 3—3 of Figure 1 and showing a portion of the side framing, side wall and floor.

Figure 4 is a section illustrating a modified structure.

The underframe illustrated is of cast metal construction and the portion shown includes a center sill 1 and transoms 4 of I section, a box shaped bolster 2, and angular side sills 5 and an end sill 3. At the intersection of each transom 4 and bolster 2 with the side sills 5, enlargements or gussets 6 are provided for attachment of suitable side framing 13.

Each side sill comprises a vertical web 8 and includes a horizontal flange 7 for directly supporting the floor boards 9. Ribs 10 and 14 are provided at the intersection of each transverse member with the side sill for assisting in maintaining the rigidity of the structure.

The vertical web 8 extends upwardly above flange 7 for a distance insuring its projecting above the top of a floor which may be carried on the flange. The car side wall 12 overlaps the outer face of web 8 and is bolted, riveted or welded to the upper portion thereof and is spaced from the floor 9. Preferably, web 8 is recessed, as indicated at 11, to permit the outer face of wall 12 to be aligned with the outer face of the body of web 8 whereby the framing 13 may be applied to the sill and the wall without any offset to accommodate the wall as would be required if the wall projected from the face of the sill.

With this construction any moisture or dirt tending to collect at the corner between the floor and wall cannot affect the side wall because of the intervening projection 15 of the sill. Most of the moisture will drain between the floor and the projection 15 and over flange 7 so as to avoid undue corrosion on this sill.

The sill will be of greater thickness than the side wall and any corrosive action will be resisted by the sill for a substantially greater period of time than such action would be resisted by the relatively thin side plates.

The floor may be of steel as well as wood and the side wall may be of wood as well as steel and Figure 4 illustrates a modified structure in which the angular sill 20 has an upwardly extending rib 21 offset from the depending leg of the sill for attaching the side wall 22 and the inwardly extending leg of the sill supports the metal floor plate 23. As in the previously described structure, there is no crevice between the floor and the side wall and any moisture running down the wall and between it and flange 21 will drain over the sill and not be retained in a pocket to set up corrosive action on the wall.

In this structure the flange 21 is offset inwardly a substantial distance from the

outer face of the sill so as to accommodate the relatively thick wall boards and leave their outer faces flush with the outer face of the sill so as to utilize a straight framing member 24.

Obviously, both floor and wall may be of wood or of steel plate and various other changes in the details of the construction may be made without departing from the spirit 10 of the invention and I contemplate the exclusive use of such modifications which come within the spirit of my invention as expressed in the claims.

I claim:

15. 1. A sill for railway vehicle underframe including an element for mounting flooring and a member projecting substantially above said element for attachment of an upright wall above the level of the top of the flooring.

20. 2. In a sill for a railway vehicle underframe, a vertical web arranged to mount a side wall on the exterior face of its upper portion, and a flange projecting inwardly 25 from said web for mounting a floor below the top of said wall mounting portion.

30. 3. In a sill for a railway vehicle underframe, an upright element adapted to mount a vehicle wall on its outer face, and a member projecting from its inner face for mounting a vehicle floor.

35. 4. A sill for a railway vehicle underframe including a substantially horizontal flange for mounting flooring, and an upright web adapted to mount wall material on its outer face, said sill being shaped to prevent extraneous particles from being trapped between said flooring and said wall material.

40. 5. In a railway vehicle, a framing sill having horizontal and vertical webs, flooring mounted on said horizontal web, and an upright wall attached to the outside of said vertical web, said vertical web being extended above the level of the top of said flooring and 45 adapted to prevent extraneous material accumulating on said flooring from contacting with said wall.

50. 6. In a railway vehicle underframe, a transom, a side sill, and a reinforcing rib at the intersection of said sill and said transom, said sill including an inwardly extending horizontal flange merging with the upper surface of said transom and adapted to mount flooring, and an upright web extending 55 above the upper surface of said flooring and arranged for attachment of an upright wall to space the same from said flooring.

60. 7. In a railway vehicle underframe, a transom, a side sill, and a gusset projecting from said sill adjacent its intersection with said transom and adapted to mount a side frame member, the upper surface of said transom being adapted to mount flooring, and 65 said sill including a vertical web merging with said gusset and having its upper surface

adapted for attachment of an upright wall and to maintain the same spaced from said flooring.

8. In a railway vehicle underframe, a side sill, a transom having an upper surface adapted to mount flooring, and a gusset depending from said sill adjacent its intersection with said transom, said sill having an upright web merging with said gusset and said web and gusset cooperating to form a surface for mounting a sideframe member, and said web having a recess in its upper edge and spaced from the upper surface of said flooring for attachment of a side wall. 70

9. In combination in a railway vehicle, a transom including an upright portion and a horizontal flange adapted to mount flooring, a side sill including a vertical web, a gusset located at the end of said transom and merging with said vertical web, a reinforcing rib extending between said gusset and the lower edge of said transom, said gusset and vertical web cooperating to form a surface for mounting a sideframe member, and a wall attached to said side frame member and said vertical web, said vertical web intervening between said wall and said flooring. 80

10. In a railway vehicle, an under frame sill, a floor supported thereby, said sill having an element projecting above the level of said floor for attachment of an upright wall with the joint between said element and wall above said floor. 85

11. In a railway vehicle, a cast metal sill, a sheet metal wall mounted thereon, flooring mounted on said sill, said sill having an element located between said wall and said flooring to prevent corrosion of said wall due to deposits of matter between said flooring and sill. 90

12. In a railway vehicle, a cast metal sill having a substantially horizontal flange and an upright web, a sheet metal wall secured to said web, flooring mounted on said flange, said web being located between said wall and said flooring to prevent corrosion of said wall due to deposits of matter between said flooring and sill. 105

13. In a railway vehicle, a cast metal sill having an upright element, a sheet metal wall secured to said element, flooring mounted on said sill, said element being located between said wall and flooring to prevent corrosion of said wall due to deposits of matter between said flooring and sill. 110

14. In a railway vehicle, a floor, a sheet metal wall, a cast metal sill having a member for supporting said floor and an upright element extending above the level of said floor, said wall being secured to said element, and said element being located between said wall and said flooring to prevent corrosion of said wall due to deposits of matter between said flooring and sill. 125

15. In a railway vehicle underframe, an 130

integral structure including a sill and a transverse member intersecting said sill, the top of said member being adapted to mount flooring, and said sill having an upright web for attachment of an upright wall and disposed so as to maintain the same spaced from said flooring.

16. A sill for a railway vehicle underframe including a vertical web, an element for mounting flooring extending laterally from said web, and an upstanding flange offset from said web for attachment of an upright wall above the level of the top of flooring mounted on said element.

17. In a railway vehicle, an underframe sill having a vertical web and a flange extending inwardly therefrom, a floor supported on said flange, an element extending upwardly from said sill and offset from the outer face of said web, an upright wall secured to the outer face of said flange, the outer face of said wall being substantially flush with the outer face of said web, and a framing member secured to the outer faces of said web and wall.

25. In testimony whereof I hereunto affix my signature this 27th day of May, 1931.

H. M. PFLAGER.
